Primary Examiner — Karen E Eldridge Powers

(57) CLAIM

The ornamental design for a comb, as shown and described.

DESCRIPTIONFIG. 1 is a bottom, front and left side perspective view of a double-sided comb showing my new design;
FIG. 2 is a top, rear and right side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an enlarged view of portion 9 shown in FIG. 2.
The broken lines in the drawings depict portions of the comb that form no part of the claimed design.1 Claim, 9 Drawing Sheets(56)
